DESIGN FOR A CAN PUNCH AND OPENER

John Westerland, Scottdale, Pa.

Application May 7, 1946, Serial No. 129,409

Term of patent 7 years

(Cl. D22—2)

To all whom it may concern:

Be it known that I, John Westerland, a citizen of the United States, residing at Scottdale, in the county of Westmoreland and State of Pennsylvania, have invented a new, original, and ornamental Design for a Can Punch and Opener, of which the following is a specification, reference being had to the accompanying drawing, forming part thereof.

Figure 1 is a perspective view of a can punch and opener, showing my new design, and

I claim:

The ornamental design for a can punch and opener, as shown.

JOHN WESTERLAND.
